Automobile door handle safety device, comprising a pair of complementary units, one unit being a metal strap having its upper end laterally bent to provide a hook, the other unit being a strap having an elongated slot to accommodate the hook, the hook being adapted to engage over the molding of the window construction of the door, the strap being adapted to be fastened to the inside of the door structure, the lower end of the strap being bent up to provide a stirrup, the stirrup being adapted to receive the free end of the handle when the handle is in its normal door-latching position, and the stirrup being adapted to prevent the handle from being accidentally depressed to a downswinging door-unlatching position.

UNITED STATES PATENT OFFICE

2,537,380

AUTOMOBILE DOOR HANDLE SAFETY DEVICE

Harold K. Travis, Alton, Ill.

Application November 21, 1947, Serial No. 787,302

1 Claim. (Cl. 292—288)

1

The present invention relates to automotive accessories and equivalent attachments, and has more specific reference to an attachment for use on the inside of automobile doors, said attachment serving to coact with the door handle to prevent accidental operation of same.

It is a matter of common knowledge that door handles are often accidentally depressed by occupants of an automobile when the latter is in motion, and as a result, accidents of a serious nature develop. What is more, young children riding in automobiles often lean against and push door handles to opening positions, whereupon the door is unlatched and swings open, and disastrous results are thus brought about.

It is evident from the foregoing description that I am aware that the art to which the invention relates, shows that it is old to provide safety-type door attachments for coaction with inside door handles. It follows that the present invention is directed to a specific form of attachment which, it is believed, is novel and destined to better achieve desired ends in this line of endeavor.

More explicitly, the invention appertains to separably and adjustably connected parts, one for coaction with the door proper and the other to coact with the door handle to prevent the latter from being accidentally swung down to open a door.

Other objects and advantages will become more readily apparent from the following description and the accompanying illustrative drawings.

In the drawings:

Figure 1 is a fragmentary elevational view of the interior of an automobile door, showing standard details of construction, and also showing a safety attachment constructed in accordance with the principles of this invention.

Figure 2 is a fragmentary sectional and elevational view on an enlarged scale, the view being on the plane of the line 2—2 of Figure 1, looking in the direction of the arrows.

Figure 3 is a perspective view of one of the parts of the attachment.

Figure 4 is a perspective view of a complementary part of said attachment.

Referring now to the drawings, wherein like numerals are employed to designate like parts throughout the views, in Figure 1, the automobile door is denoted by the numeral 6, the slideable window by the numeral 7, its operating hand-crank at 8, and the ventilator panel at 9. The operating handle for the ventilator is denoted at 10, and the so-called inside latch-controlling

door handle, the part with which we are here concerned, is denoted by the numeral 11. The purpose of the invention is to check the downward swinging movement of said inside door handle 11, whereby to prevent same from being unknowingly depressed, and causing the door to unlatch and fly open. The means provided is a simple attachment which comprises a pair of complementary units 12 and 13. The unit 12 comprises a metal strap 14 having its upper end laterally bent as at 15, and its free end bent as at 16, to provide a hook. This hook is adapted to engage over the molding of the window construction of the door, as brought in Figure 2. The bill 16 takes a position between the glass panel and that part of the molding which surrounds the glass receiving compartment built in the door. Adjacent the bend 15, I provide a screw-threaded hole 17, to accommodate a set-screw 18 which serves to hold the part, or unit 12, satisfactorily in suspending position, as shown in Figures 1 and 2. The lower end of the strap is provided with a screw-threaded stud 19. The remaining or lower unit 13 also comprises a strap of metal or equivalent material 20, having an elongated slot 21 to accommodate the stud 19 and clamping nut 22. The lower end of the strap is bent up to provide a hook or stirrup 23, which, in practice, serves to permit the free end portion of the handle 11 to be saddled therein.

In practice, by fastening the hanger unit 12 on the inside of the door structure, as illustrated in the drawings, by hooking the stirrup 23 beneath the free end of the handle, when the handle is in its normal door-latching position, and then by making proper adjustment between the two parts 12 and 13 and tightening the nut 22, the attachment is ready for action. Manifestly, with the free end of the handle seated in the stirrup, accidental depressing of same to a downswinging door-unlatching position is prevented.

Since some doors are provided with inside handles which swing up, instead of down, it is obvious that by reversing the bend which defines the hook 23, an appropriate stop and safety device would be had.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and arrangement of parts may be resorted to in actual

practice so long as no departure is made from the invention as claimed.

Having described the invention, what is claimed as new is:

An automobile door attachment for preventing accidental unlatching of an inside latch-releasing handle when once the door is closed, comprising a readily applicable and removable safety device, said device embodying an upper unit embodying an elongated rigid strap, the upper end portion 10 of said strap being bent outwardly and downwardly to provide an attaching and anchor hook suitable to coact with the stated door, the bill portion of said hook being linearly straight and parallel to the body portion of said strap, said body portion being provided with a set screw, the lower end of the body portion being free of marginal projections and having, on one side, an outstanding screw-threaded stud, and a second complementary unit comprising a rigid strap superimposed and slidable and laterally swingable on the first-named strap and having a slot, the stud extending through said slot and being provided

5 with a thumb nut for clamping the two units adjustably to one another, the lower end portion of the second-named strap being bent inwardly and upwardly to provide a stirrup-like hook which is adapted to seat and retain the free end portion of the door handle in the manner and for the purposes described.
